INCLINED WHARF FOR COKE OVEN
BATTERIES

Karl Mack, Essen, Germany, assignor, by mesne assignments, to Koppers Company, Pittsburgh, Pa., a corporation of Delaware

Application June 2, 1938, Serial No. 211,436
In Germany June 5, 1937

3 Claims. (Cl. 198—52)

The present invention relates to inclined wharfs or the like provided for chamber or retort oven batteries for the production of gas and coke, in which the coke produced in said ovens is provisionally stored and from whence the coke is delivered to a conveyor running along the lower part of the wharf.

Most of the modern coke oven plants and gas-works and especially those which are equipped with horizontal chamber ovens, are provided with the so-called quenching cars which travel over a track along the coke oven battery and into which the coke from the coking chamber is pushed. The car loaded with coke is then driven to the quenching tower, where water is sprayed over the glowing coke. The quenched coke is finally discharged from the quenching car onto an inclined wharf where the coke remains for a given time until the excessive quenching water has drained-off and the coke has steamed-out.

In order to prevent the coke from sliding-off the inclined discharge wharf, gate-like holders are provided at the lower edge of the wharf, said gates may be lifted upwards for the removal of the coke from the inclined wharf.

For the transporting the coke from the inclined coke wharf to storage or to a loading station, a belt conveyor is often used, for instance a belt conveyor made of india-rubber or another suitable material. This conveyor is so arranged that it extends along the lower edge of the inclined wharf so that the coke may be discharged from all points of the wharf onto the belt conveyor after lifting the respective finger gates.

In order to direct the coke sliding off from the wharf onto the comparatively narrow belt conveyor, it is usual to arrange essentially vertical guiding walls extending parallel to the conveyor belt at the side of the belt conveyor facing the wharf. Such coke sliding from the wharf as does not immediately reach the conveyor belt, is pushed against these guiding walls and falls back onto the belt, where it distributes more or less uniformly.

However, the usual arrangement of guiding plates along the conveyor has the disadvantage that coke pieces easily stick between the guiding walls and the edge of the conveyor belt, thus tearing off the india rubber cover of the belt.

In order to avoid such destruction, it has been tried to have the conveyor belt run as closely as possible along the guiding walls and to support the belt by a multitude of rollers which control the direction of movement of the belt and its exact position relatively to the guiding walls.

The rollers are mainly intended to prevent a sagging of the belt, as it may easily happen that, with the sagging of the belt, intervening spaces between the belt conveyor and the adjacent guiding wall will be formed, into which coke pieces may penetrate and accumulate. By the arrangement of a greater number of supporting rollers, the conveyor cost is considerably increased quite apart from the fact that frequent damages to the belt will occur notwithstanding the greater number of supporting rollers.

Another disadvantage of the hitherto known arrangement of belt conveyors for coke wharfs or the like consists in that the coke sliding away from the wharf takes a direction transverse to the movement of the belt conveyor. As the coke pieces impinge upon the belt, the direction of movement of the coke is practically deflected at a right angle. This deflection causes a considerable stress upon the conveyor cover and although the conveyor cover is usually strengthened for the above reasons, for instance by increasing the thickness of the rubber layer, the wear and tear on the cover or surface layer of the india-rubber conveyor belts at coke wharfs, and in similar cases, is so considerable that the india-rubber belt has to be replaced frequently.

Now, the main object of my present invention is to provide such improvements which will eliminate the before mentioned difficulties of the conveyor belts or the like at coke wharfs and other contrivances when similarly unfavorable conditions are prevailing and which has further advantages as may be seen from the following description.

The principal improvement according to my present invention is to arrange at the lower edge of the coke wharfs of coking plants, or gasworks, or similar contrivances fitted with belt conveyors, a multitude of adjustable guide plates extending essentially in the direction of the upper side of the wharf, said guide plates being situated above the conveyor belt, and being provided on their upper side, with adjustable projections which will deflect the coke sliding over the said guide plates. Another important feature of my invention is that the inclined adjustable projections of the guide plates are bent similar to a ploughshare in such a way that the material pressing against the said projections is not only directed laterally but at the same time also a little downwardly during the course of its descent after leaving the wharf so that the material may preferably accumulate in the centre of the belt conveyor.

- When making use of the present invention, it is no longer necessary to provide guiding plates at the sides near the belt conveyor, since the material cannot spill over the belt, due to the peculiar shape of the guide plates and their upper projections. The wear and tear of the conveyor belt is reduced, when adopting my present invention, to such an extent that the belt conveyor shows a considerably improved stability.
- With the above and other objects and features of my present invention in view, I will now describe a preferred embodiment of my invention on the lines of the accompanying drawing, in which
- Figure 1 is a vertical section through a coke discharge wharf constructed according to my invention.
- Figure 2 is a view from above of the guide faces of the guide plates.
- On the drawing the coke oven battery, coke quenching car, etc. are omitted as such contrivances are well-known to all those skilled in the art.
- The upper side of the coke discharge wharf, consisting of cast-iron plates or the like, has been marked 1 on the drawing. The wharf itself is formed by a frame 2 which is designed so that the end of the wharf projects into a channel 3 through which runs a belt conveyor 4. The upper strand of the belt 4 is held by supporting rollers 5 and the lower strand by supporting rollers 6. As usual, the upper supporting rollers within the range of the coke wharf are constructed in such a way that the belt conveyor is bent like a trough.
- On the discharge wharf 1, the material marked 7, for instance coke, is held by the finger gates 8 which are fastened to the carrying levers 9 in such a way that they can be lifted from the service alley 10 into the position marked in dotted lines at 11.
- After lifting the finger gates 8, the coke, in freely sliding off from the wharf at 11 comes first onto the guide plates 12 which are substantially situated in the direction of the upper side of the wharf 1. The guide plate 12 can be turned round a horizontal axis and for this purpose they are supported adjustably by being pivoted at point 13 on suitable projections 14 of the wharf frame 2. Preferably, these guide plates 12 are provided all along the whole length of the wharf 1. It is, however, also possible to arrange the novel mechanism so that, instead of being arranged in fixed relation to the wharf for rotation about the axis 13, the guide plates are carried movably and slewably on a track, so that a certain number of guide plates 12, possibly combined with one another into one unit, may be moved along the wharf to the various points of the wharf where it happens that the coke is to be discharged.
- On the upper side of the guide plates 12, projections or guide deflectors 15 are arranged in such a way that they extend slantingly in the direction of conveyance of the belt 4. Figure 2 of the drawing shows by arrow 16 the direction of conveyance of the belt conveyor 4. It can be seen from Figure 1 that the guide plates 12 and the guide deflectors 15 extend over the belt conveyor 4.

The guide deflectors 15 (see Figure 2) are bent

at the top similar to a ploughshare. Consequently, the walls of the guide deflectors 15 deflect the coke, while it is sliding after leaving the edge of the wharf 1 and impinging against the sides of the deflectors, not only laterally in the direction of conveyance of the belt but also downwards. In this way, a uniform accumulation of the material in the centre of the india-rubber belt conveyor is obtained.

The guide deflectors 15 have at their base, 10 openings 17 formed as oblong holes which are penetrated by the fastening screws for the guide deflectors. It is, therefore, possible to adjust the angular position of the guide deflectors 15 with respect to the guide plates so that the adjustment is in exact accordance with the nature and the sliding speed of the material. If the inclined or angular position of the guide deflectors has to be altered considerably, the deflectors are suitably connected movably about a point with 20 the guide plate.

I have in the above described the present invention on the lines of a preferred embodiment thereof, but my invention is not limited in all its aspects to the mode of carrying it out as described and shown, since the invention may be variously embodied within the scope of the following claims.

I claim:

1. Coke discharge wharf for coke oven plants 30 or the like, comprising a belt conveyor travelling along the lower edge of the wharf, a guide plate movably mounted on the lower edge of the wharf and extending over said conveyor, said plate being swingable about a horizontal axis so as to 35 form a lower extension of the wharf, said plate being further provided on its upper side with projections, said projections being so designed that the material sliding off the wharf is directed in the direction of movement of the conveyor. 40

2. Coke discharge wharf for coke oven plants 45 or the like, comprising a belt conveyor travelling along the lower edge of the wharf, a guide plate movably mounted on the lower edge of the wharf and extending over said conveyor, said plate being swingable about a horizontal axis so as to 50 form a lower extension of the wharf, said plate being further provided on its upper side with adjustable projections, said projections being so designed that the material sliding off the wharf is directed in the direction of movement of the conveyor.

3. Coke discharge wharf for coke oven plants 55 or the like, comprising a belt conveyor travelling along the lower edge of the wharf, a guide plate movably mounted on the lower edge of the wharf and extending over said conveyor, said plate being swingable about a horizontal axis so as to 60 form a lower extension of the wharf, said plate being further provided on its upper side with projections, said projections extending cross-wise of the guide plate at an angle in the direction of movement of the conveyor and being curved in cross-section to form an upwardly directed back wall terminating in an overhanging top wall 65 projecting from the back wall in the direction of movement of the conveyor.

KARL MACK.
